UNITED STATES PATENT OFFICE.

LUZERNE M. BOLLES, OF NEW YORK, N. Y.

SCRUBBING-BRUSH.

SPECIFICATION forming part of Letters Patent No. 242,106, dated May 31, 1881.

Application filed April 20, 1881. (Model.)

To all whom it may concern:

Be it known that I, LUZERNE M. BOLLES, a citizen of the United States, residing at 163 Canal street, in the city of New York, in the county and State of New York, have invented a new and useful Improvement in Tubular Rubber Scrubbing-Brushes, of which the following is a specification, reference being had to the accompanying drawings, in which—

- 10 Figure 1 is a view of the under side of my brush, showing the arrangement of the rubber tubes; and Fig. 2 is a sectional view of the scrubber, showing the rubber tubes inserted in the wood-holder.
- 15 A A are small flexible rubber tubes. B is a larger tubular rubber placed in the center of the block and containing a sponge, C. D is the wooden block, and E is a wooden or metal cover.
- 20 Similar letters of reference indicate corresponding parts.
- 25 The object of my invention is to make a scrubbing-brush in such a manner that when the brush is drawn across a surface to be cleaned the bending of the tubular rubbers will expel the air from the inside of the tubes, and as they straighten up form suckers, thereby extracting the impurities and dirt from the article worked upon.

Any number of tubes may be used. In my drawings I have shown one larger central tube with a sponge in same, but more than one may be used, if preferred. My object in using a larger central tube is for a twofold purpose. First, so that a goodly quantity of moisture may be retained in the sponge; and, secondly, because in moving the brush across a surface it materially assists in securing a uniform rubber of the whole surface of the brush.

The block D may be made of wood or any other suitable material. As shown, it is made of wood, the holes in same to receive the rubbers being made largest on the upper sides, so that when the cover is fastened on it secures the tubes in place and makes them air-tight.

Having thus described my invention, what I claim as new, and desire to secure by Letters Patent, is—

A scrubbing-brush composed of a perforated block provided with projecting flexible tubular rubbers, substantially in the manner and for the purpose described.

LUZERNE M. BOLLES.
